(57) **CLAIM**

The ornamental design for a slow feeder bowl, as shown and described.

DESCRIPTION

FIG. 1 is a perspective view of a slow feeder bowl showing my new design;

FIG. 2 is an exploded perspective view of a slow feeder bowl thereof;

FIG. 3 is a perspective view of a slow feeder bowl in a folded state;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of the bone detail portion of the slow feeder bowl indicated in FIG. 2; and,

FIG. 11 is an enlarged view of the bone detail portion of the slow feeder bowl indicated in FIG. 2.
